FLEXIBLE ROLLING CLOSURE FOR
CABINETS

William J. Dobkin, Jackson Heights, N. Y.

Application April 14, 1945, Serial No. 588,337

8 Claims. (Cl. 312—297)

1

The present invention relates to cabinet closures, and more particularly to the door structure of cabinets of the general type, such as those which are employed in kitchens, laboratories and the like, and which are usually installed between the ceiling and the sink or working counter.

In order to open or close the ordinary hinged door on a wall cabinet, closet or cupboard, it is necessary for a person to step back sufficiently to clear the swinging door. This may be inconvenient, especially where the space in front of the cabinet is restricted, as in the case of small pantries. Also, these doors are very often thoughtlessly left ajar, and are thereby a source of facial or head accidents. Moreover, when a hinged cabinet door is opened, the full height of the interior of the cabinet is exposed, even though access to the lower shelves alone is required, so that the whole interior is unnecessarily exposed to dust, fumes, etc. The articles more frequently handled are usually stored in the lower shelves of the cabinet, so that it is rarely necessary to gain access to the upper shelves of said cabinet.

One object of the present invention is to provide a new and improved closure for a cabinet of the general type referred to.

Another object is to provide a flexible cabinet closure structure of the rolling type, which eliminates the disadvantage of a hinged door structure, which can be easily and conveniently manipulated, which can be operated so that only selected portions of the cabinet from the bottom up are exposed, which can be easily mounted in a cabinet frame or dismounted therefrom as a unit, which maintains the door against drifting movement, which occupies a minimum of space in the interior of the cabinet, and which lends itself effectively to ornamental design.

Various other objects, features and advantages of the invention will be apparent from the following particular description, and from an inspection of the accompanying drawings, in which:

Fig. 1 is a partial front elevation of a cabinet which has a flexible door structure embodying the present invention, and which is shown with parts of the front wall broken away to reveal part of the reel mechanism behind said wall;

Fig. 2 is a vertical section of the cabinet taken along the lines 2—2 of Fig. 1;

Fig. 3 is a top plan view showing details of the reel mechanism for the flexible door;

Fig. 4 is a vertical section of the reel device taken along the lines 4—4 of Fig. 1, but shown on a larger scale;

2

Fig. 5 is a detailed section of the stop mechanism for predetermining the limiting open and closed positions of the flexible door;

Fig. 6 is a face elevation with parts broken away showing a clutch mechanism by which the flexible door is automatically maintained in any selected open position without the necessity of applying manual holding force;

Fig. 7 is a radial section through the clutch mechanism.

Referring to the drawings, the present invention is shown for the purpose of illustration applied to a cabinet, closet or cupboard 10 of the general type, such as that which is supported on the walls of a kitchen or laboratory above the floor. Such a cabinet, for example, would be supported above a kitchen sink, a wall table or a laboratory counter, and would be of such height that the interior of said cabinet would be accessible to a person standing up without the necessity of bending down. This cabinet 10 is shown comprising a rear wall 11, and a front wall 12 provided with one or more rectangular door openings 13, two of these being shown disposed alongside of each other. It must be understood, however, that any number of these door openings 13 disposed side by side may be provided according to the size of the cabinet.

Each of the door openings 13 is framed on its sides by stiles or upright front wall frame pieces 14, along the top by a cross front wall frame piece 15, and along the bottom by a cross front wall frame piece or sill 16. The frame pieces 15 conjointly form a continuous comparatively wide panel across the top of the cabinet 10, and the frame pieces or sills 16 conjointly form a continuous comparatively narrow panel across the bottom of the cabinet.

The cabinet 10 is shown provided with the usual vertically spaced horizontal shelves 17 supported therein in any well-known manner, and dividing said cabinet into a series of superposed storage compartments.

As a feature of the present invention, each of the door openings 13 is closed by a flexible rolling door or closure 20 having its upper end secured to a reel device 21 on which it can be wound for opening movement, or from which it can be unwound for closing movement.

The flexible rolling door 20 may be of the type such as that commonly used in roll-top desks, and is shown comprising a canvas or other suitable flexible backing sheet 22 having horizontally attached thereto in any suitable manner reinforcing strips or slats 23 of wood, metal or plastic. In cases where it is desired to ventilate the cabinet without exposing the contents thereof, the

canvas backing 22 may be eliminated, and the strips or slats 23 may be linked together.

The reel device 21 on which the upper end of the flexible door 20 is secured and wound, is mounted on a bracket 26, shown in the form of a U, and having a pair of side arms 27 interconnected by a cross member 28 removably supported on the inner face of the upper door frame 15. For removably supporting the bracket 26 in position without the use of bolts, nuts or other fastening means visible from the outside of the upper door frame piece 15, there is secured to the inner face of said door frame piece a plurality of fingers or hooks 32, and the cross-piece 28 of the bracket 26 is provided with a corresponding plurality of holes 33. Each of the hooks 32 is shown with a shank 34 affixed to the inner face of the door frame piece 15 by any suitable means, as for example, by welding, and with a finger 35 extending obliquely upwardly from said shank. The bracket 26 with the reel assembly 21 supported thereon is removably hung on the hooks 32, as shown in Fig. 4, with their fingers 35 extending through respective bracket holes 33, and will be firmly retained in this mounted position until it is desired to dismount the bracket and the reel assembly from the cabinet wall.

The reel device 21 includes an axle 37 which is supported for rotation on the side bracket arms 27 through a trunnion and bearing arrangement to be described, and which has rigidly secured thereto a pair of reel discs 38. The sides of the upper end of the flexible door 20 are secured to these two reel discs 38 respectively.

In order to wind the flexible door 20 neatly about the reel discs 38 without any radial offsets or bulges in the wound section of said door, each of these reel discs has a spiral periphery 40, and the end of said flexible door is secured to said periphery near the base section of its radially offset section 41. The door 20 is secured to the reel discs 38 near this reel disc section by any suitable means, as for example, by means of fastening pins 42 passing through the end door slats 23, and through the peripheral flanges of said reel discs.

The flexible door 20 is held along its sides close to the inner edges of the stiles 14 by means of guides 45. These guides 45 may be in the form of angle irons secured to the inner faces of the stiles 14 near their edges by any suitable means, as for example, by welding, and forming with said inner faces guide channels into and along which the sides of said door are adapted to travel in their vertical movement. The upper ends 46 of these guides 45 are desirably flared to facilitate threading of the door 20 therein. These guides 45 serve not only as runways for the sides of the door 20, as said door is moved up and down over the door opening 13, but also serve to maintain said door against the inner face of the stiles 14, so that the sides of said opening are substantially sealed by said door against the entry of dust or fumes.

As another feature of the present invention, the door 20 is manipulated into open or closed position through the operation of a rotatable member 50 desirably in the form of a hand-knob, mounted on one of the stiles 14 framing one side of the opening 13, and disposed in the lower end thereof, so that said knob is easily accessible for manipulation. The reel device 21 is operated from the knob 50 to wind or unwind the flexible door 20 by means of a transmission between said door-knob 50 and said reel device 21. In the

specific form shown, this transmission includes a sheave or pulley 51 on the inner side of the stile 14, having a drive connection with the knob 50 through a clutch to be described, a sheave or pulley 52 fixed to one end of the reel axle 37, a pair of idler pulleys 53 mounted for rotation on a stud shaft 54 affixed to one of the side bracket arms 27, and an endless chain or belt 55 passing over the two pulleys 51 and 52, and having one side run passing over one of the idlers 53, and its other side run passing over the other idler pulley 53. In this arrangement, the idler pulleys 53 serve not only to locate the two side runs of the belt 55, but also serve as slack adjustment for said belt. The size ratio between pulleys 51 and 52 is such that one or two turns of the operating knob 50 will completely open or completely close the cabinet door 20.

Easy operation of the door 20 through manipulation of the knob 50 is assured by means of a compensating spring 56 in the form of a coil spring loosely encircling one end of the axle 37 between a bracket side arm 27 and an adjoining disc wheel 38, and having its ends secured to said side arm and said reel disc respectively. This spring 56 serves to counterbalance the weight of the door 20 when said door is in partly closed position.

To prevent the door 20 from drifting up or down due to any slight variance between the weight of the door and the tension of the compensating spring 56, there is provided between the operating knob 50 and the pulley 51 a clutch or reel locking device 57, shown in detail in Fig. 6. This device 57 comprises an outer clutch ring 60 affixed to the inner face of the cabinet stile 14, and an inner clutch disc 61 secured to the pulley 51, and defining with the outer ring a recess 59. The inner disc 61 has an outer circular periphery 62 concentric with an inner circular periphery 63 on the outer ring 60, and has a flatter section 64 on which rest two spherical balls 65 and 66. A coil spring 67 disposed in the recess 59 between the two balls 65 and 66 normally urges these balls apart. The radial distance between the circular peripheries 62 and 63 of the two members 61 and 60 is slightly smaller than the diameter of the balls 65 and 66, while the radial distances between the flatter section 64 of the disc 61 and the inner circular periphery 63 of the outer ring 60 is slightly larger than the diameter of these balls. As a result of the spreading action of the spring 67 on the two balls 65 and 66, these balls are normally wedged between the ring 60 and the disc 61 in the position shown in Fig. 6, thus locking said disc against rotation. Since the disc 61 is fast to the pulley 51, said pulley is also locked against rotation, so that the reel 21, through the medium of the belt 55, is held against rotation. The door 20 is thereby retained in any selected position against drifting movement.

In order to release the reel locking device so that the reel 21 is permitted to turn, there is provided a floating disc 70 having a web 71 secured to the shaft 72 of the operating knob 50, and a circular axial flange 73 extending into the recess 59 between the peripheries 62 and 63 of the members 61 and 60. This flange 73 has a section thereof cut away to receive the ball and spring assembly 65, 66 and 67 between the ends thereof.

In order to establish a lost motion drive connection between the floating disc 70 and the clutch disc 61, said clutch disc 61 has rigid there-

with a pin 74 extending into an elongated circular slot 75 in the web 71 of said floating disc. While the hand-knob 50 is free from manipulation, the pin 74 extends substantially centrally of the slot 75, as shown in Fig. 6.

With the reel locking device 57 as described, when, for example, it is desired to raise the door 20, the knob 50 is rotated clockwise, as shown in Fig. 6, to rotate the floating disc 70 in a corresponding direction. The initial clockwise movement of the floating disc 70 will cause one end of its flange 73 to engage the wedge ball 65, and thereby move said ball towards the wider section of the recess 59 between the members 60 and 61, thus freeing the disc 61 to which the pulley 51 is affixed for clockwise rotation. This initial movement of the floating disc 70 is not transmitted to the disc 61, because of the lost motion connection between the elongated slot 75 and the pin 74. A further clockwise rotation of the knob 50 will cause the pin 74 to be engaged by the end of the elongated slot 75, so that the clutch disc 61 is driven clockwise. This clockwise movement of the clutch disc 61 is transmitted to the pulley 51, and in turn to the reel device through the belt 55, as already described.

When it is desired to lower the door 20, the knob 50 is rotated in a counterclockwise direction (Fig. 6), and this will in turn first release the ball 66 from wedging position in the recess 59 between the two members 60 and 61, and then will establish a drive connection between the disc 61 and the operating knob 50 through the pin and slot arrangement 74 and 75, so that further counterclockwise rotation of said knob will cause said door to be lowered.

As another feature of the present invention, means are provided for limiting the opening and closing movement of the door 20, so that said door will come to a dead stop when it is completely closed or when it is completely open, regardless of any manipulation of the turning knob 50. This limiting device, shown in Figs. 3 and 5, comprises a feed screw 80 passing through one of the side bracket arms 27, and having threaded thereon a nut 81 which is rigidly attached to the inner face of said side bracket arm by any suitable means, and which serves as one of the limit stops for the door 20. This feed screw 80 is adjustably held in position against axial and rotational movement by means of a lock nut 82 threaded on said screw, and engaging the outer face of the side bracket arm 27. Integral or otherwise rigid with the inner end of the screw 80 is a head 83, serving as the other limit stop for the door 20.

The reel axle 37 is hollow, and the two stops 81 and 83 on the screw 80 extend into one end of said axle with a snug rotative fit, and thereby conjointly serve as a trunnion to rotatably support said axle at said end. The other end section of the axle 37 is journaled in one of the side bracket arms 27 in any suitable manner.

As the turning knob 50 is rotated, the axle 37 is rotated in a corresponding direction. In order to bring the axle 37 to a dead stop when the door 20 reaches the limit of its open or closed position, there is threaded on the feed screw 80 a sleeve 85. This sleeve 85 has a lug 86 extending longitudinally thereof and projecting therefrom through an elongated slot 87 along the axle 37, so that a connection is established between the sleeve 85 and the axle 37, causing said sleeve to rotate with said axle while permitting it to slide axially therealong. In order that the axle 37

come to a dead stop at the end of the movement of the sleeve 85, the ends of said sleeve are provided with helical clutch conformations 88 and 89, each defining a clutch tooth, and the two fixed stops 81 and 83 are provided with corresponding helical clutch conformations 90 and 91 adapted to interlock through interengaging clutch teeth with the conformations 88 and 89 respectively, when the sleeve 85 reaches the ends of its slide movement. The pitch of the helical conformations 88, 89, 90 and 91 corresponds to that of the feed screw 80, and the position of the sleeve 85 is so adjusted with respect to the stops 81 and 83 as to cause the conformations 88 and 90 and the conformations 89 and 91 to come to full conforming interlocking engagement as shown in Fig. 5 when the sleeve 85 reaches the end of its slide movement.

With the door stop limiting mechanism described, as the reel 24 is rotated in one direction, its axle 37 is correspondingly rotated, so that the sleeve 85 through the lug and slot connection 86 and 87 is rotated around the feed screw 80. This causes the sleeve 85 to be fed axially along the feed screw 80 until it reaches either stop 81 or 83, according to the direction of movement of the reel 24. When this sleeve 85 reaches the end of its movement, the two complementary clutch conformations 88 and 90 or 89 and 91 come into full interlocking engagement, so that the sleeve 85 is locked against further rotation. This in turn locks the reel axle 37 against rotation, so that the door 20 remains in its completely open or completely closed position. When the reel 24 is rotated in an opposite direction through proper manipulation of the knob 50, then the reel axle 37 will be rotated in a direction to release the sleeve 85 from locking engagement with one of the stops 81 or 83, and cause it to move towards locking engagement with the other stop.

By loosening the lock nut 82 and adjusting the axial position of the feed screw 80 with respect to the fixed stop 81, the position of the other stop 83 with respect to said stop 81 is correspondingly adjusted, and the limiting travel of the door 20 is accordingly varied.

By means of the construction of the present invention, the door 20 can be raised by simple manipulation of the turning knob 50, so as to progressively expose the interior of the cabinet 10 from the bottom up. No backstepping of the person manipulating the turning knob 50 is necessary, nor is there any possibility of head accidents from the door 20, as in the case of the ordinary hinged cabinet door. Furthermore, the opening of the door 20 progressively from the bottom up permits exposure of only the bottom shelves where the articles more frequently handled are stored, while the upper shelves, where the articles less frequently handled are stored, remain protectively covered by the partially closed door 20.

Moreover, a flexible rolling door 20, such as that of the present invention, lends itself effectively to ornamental design. For example, the door 20 may be constructed and designed to match the Venetian blinds of a kitchen or other room where the cabinet 10 is mounted, and the door slats 23 may be colored or otherwise ornamented to conform with any desired decorative pattern.

When it is desired, for example, to clean the interior of the cabinet 10, or to repair the flexible door structure, the whole structure may be

removed as a unit from the cabinet, by the mere operation of lifting the mounting bracket 26 off the supporting hooks 32.

Although only one flexible door structure is shown, it must be understood that each of these structures would be repeated for each door opening 13.

As many changes can be made in the above device, and many apparently widely different embodiments of this invention can be made without departing from the scope of the claims, it is intended that all matter contained in the above description or shown in the accompanying drawings shall be interpreted as illustrative and not in a limiting sense.

What is claimed is:

1. In a cabinet having a door opening, a flexible rolling door for said opening, a winding reel for one end of said door supported on an axle and rotatable therewith, and stop means for blocking rotation of said reel when said door reaches either one of its limiting positions, and comprising a member extending into said axle from one end thereof, and serving as a trunnion for said axle.

2. In a cabinet having a door opening, a flexible rolling door for said opening, a winding reel for one end of said door rigidly supported on an axle having a slot extending lengthwise thereof, and stop means for blocking rotation of said reel when said door reaches either one of two limiting positions, and comprising a feed screw extending lengthwise into said axle and supported against rotation, a sleeve threaded on said screw in said axle, and having a member projecting therefrom into said slot, whereby said sleeve rotates with said axle but is slideable therealong, and stop members adapted to be engaged by said sleeve when said door reaches either one of said limiting positions, said sleeve and said stop members having complementary clutch teeth conformations adapted to interlock when said sleeve reaches said stop members, whereby further rotation of said sleeve, and in turn said reel, is blocked, said stop members being adjustable with respect to said sleeve to alter the limiting positions of said door.

3. In a cabinet having a door opening, a flexible rolling door for said opening, a winding reel for one end of said door, manual control means for turning said reel a pair of stop members for blocking rotation of said reel when said door reaches either one of two preselected limiting positions independently of said control means, means for adjusting either of said stop members to adjustably vary selectively either one of said door limiting positions, and means for operatively supporting said winding reel in any adjusted positions of said stop members.

4. In a cabinet having a door opening, a flexible rolling door for said opening, a winding reel for one end of said door, manual control means for turning said reel, and clutch means holding said door in any selected position against drifting movement.

5. In a cabinet having a door opening, a flexible rolling door for said opening, a winding reel for one end of said door, clutch means holding said door in any selected position against drifting movement, and a control member for releasing said clutch and turning said reel.

6. In a cabinet having a door opening, a flexible rolling door for said opening, a winding reel

for one end of said door, a manually rotatable control member, and a drive transmission between said control member and said reel for rotating said reel upon rotation of said control member, and including a clutch member having a fixed element, a rotatable element constituting a drive part of said transmission, a coupling between said rotatable element and said control member, means for normally coupling said rotatable clutch element to said fixed element to hold said door in any selected position against drifting movement, and means for releasing the coupling engagement between said elements when said control member is turned to cause rotary movement of said reel through said control member.

7. In a cabinet having a door opening, a flexible rolling door for said opening, a winding reel for one end of said door, manual control means for turning said reel, stop means for blocking further rotation of said reel when said door reaches a limiting position, and comprising a feed screw, means supporting said feed screw for axial adjusting movement, a sleeve threaded on said screw and rotatable with said reel over said feed screw, a stop member adapted to be engaged by said sleeve when said door reaches said limiting position, said stop member being rigid with said feed screw, whereby the limiting position of said door can be adjusted by adjusting the axial position of said feed screw, and means for supporting said winding reel in any axially adjusted position of said feed screw.

8. In a cabinet having a door opening, a hollow axle, a flexible rolling door for said opening, a winding reel for one end of said door supported on said axle and rotatable therewith, stop means for blocking rotation of said reel when said door reaches substantially either completely closed or completely opened position, and comprising a feed screw extending lengthwise into said axle, a sleeve threaded on said screw in said axle, and having a connection with said axle whereby said sleeve rotates around said feed screw with said axle but is slideable therealong, stop members along the path of sliding movement of said sleeve adapted to be engaged by said sleeve when said door reaches substantially either completely closed or completely opened position, one of said stop members being rigid with said screw, means supporting said screw for axial adjusting movement in said axle to permit adjustments in the relative position of said stop members, and means for supporting said winding reel in any axially adjusted position of said screw.
